FOUNDRY SAND SIFTING AND FLASK-FILLING APPARATUS

Harry H. Rawson, Spokane, Wash.

Application September 6, 1944, Serial No. 552,906

1 Claim. (Cl. 209—240)

1

This invention relates to a flask-filling apparatus and it is one object of the invention to provide an apparatus by means of which flasks used by moulders in a foundry may be quickly and very easily filled with sand which has been sifted in order to remove foreign matter.

Another object of the invention is to provide a flask-filling apparatus wherein a hopper for holding sand may be supported above a frame mounted for reciprocating movement over a bag and carrying a screen or riddle through which the sand passes so that only clean sand will drop into the bag.

Another object of the invention is to provide the frame with a riddle support so mounted that it may be released and swung downwardly to inoperative position allowing removal of the riddle for cleaning and replacement after cleaning.

Another object of the invention is to provide the apparatus with a bag for receiving clean sand, the bag being tapered toward its lower end which is open and surrounded by a ring having handles by means of which the lower portion of the bag may be turned upwardly and thus closed to retain sand in the bag.

Another object of the invention is to provide improved means for holding the lower portion of the bag in folded position after a flask has been filled with sand.

Another object of the invention is to provide an apparatus of this character which is simple in construction and very easy to operate.

In the accompanying drawings:

Fig. 1 is a side elevation of the flask-filling apparatus with portions in vertical section.

Fig. 2 is a view on the line 2—2 of Fig. 1.

Fig. 3 is a sectional view on an enlarged scale taken through the riddle and its support, on the line 3—3 of Fig. 2.

Fig. 4 is a fragmentary view showing the lower portion of the hopper and the riddle-carrying support suspended therefrom.

This improved flask-filling apparatus has a base 1 carrying a vertically adjustable support or lift 2 upon which the flask 3 to be filled with sand is placed. This lift has a conventional pneumatic lift construction and is actuated by the usual lever 4 so disposed that it may be operated by pressure applied to it by an operator standing in front of the apparatus. A second pneumatic lift 5 is located back of the lift 2 and its cylinder 6 carries a plate 7 which is swung over the flask after the flask has been filled with sand. The plate is carried by a threaded stem 8 which passes through a sleeve 9 and carries a

2

nut 10 for resting upon the sleeve and supporting the plate in a vertically adjusted position. The portion of the machine so far described is conventional and, at the present time, it has been customary to fill the flasks with sand scooped from a pile on the floor with a shovel. This has been found unsatisfactory as dirt and other foreign matter is liable to become mixed with the sand and deposited in the flasks as sand is shoveled into them.

In the improved apparatus, the sand as received at a foundry is placed in a hopper 11 in any desired manner, where it is stored before being used. This hopper is carried at the upper end of a standard 12 by an arm 13 and from the hopper extends a bracket 14 braced by an arm 15 bearing against the standard. The bracket 14 carries a cylinder 16 in which a piston 17 is reciprocated by air 18 controlled by a valve 19, the cylinder 16 and its piston 17 being of conventional air-actuated design. At its outer front end the piston 17 is fixed to a frame 20 formed of strong metal and preferably circular in shape. This frame or ring 20 is provided at opposite sides with trunnions 21 which engage through eyes at lower ends of links 22 suspended from trunnions 23 at opposite sides of the hopper 11 and when the piston 17 is reciprocated in the cylinder 16, reciprocation will be imparted to the frame or ring 20.

Within the frame or ring is disposed a screen or riddle 24 of appreciably smaller diameter than the ring so that it fits loosely therein and may be very easily inserted or removed. The riddle rests upon a frame or support 25 formed of metal rod and of oblong shape. This support or frame extends diametrically of the ring 20 and has its rear cross bar mounted through a bearing bracket 26 at the back of the ring and the cross bar has its front end formed with a forwardly projecting slotted tongue 27 to receive a threaded stem 28 pivotally carried by a bracket 29 so that it may be swung vertically into engagement with the tongue and the wing nut 30 then tightened to secure the frame 25 in its raised or operative position where it will support the riddle in the ring 20. When the ring is reciprocated by action of the piston the riddle will be shaken and stones and trash held in the riddle while lumps of sand will be broken up and all of the sand in the riddle will pass through it. By loosening the nut and swinging the bolt 28 upwardly out of the tongue, the frame may be lowered and the riddle removed, cleaned, and replaced, and the support or frame 25 again secured in its raised position.

Under the ring 20 is a circular frame 31 formed of inner and outer rings 32 and 33 between which is secured the upper end of a bag 34 formed of fabric and tapered toward its lower end, which is open so that sand may flow out of the bag and into the flask over which the lower end of the bag terminates in spaced relation thereto. The outer ring carries a hinge bracket 35 having at its outer rear end a head 36 formed with a toothed inner side face for interfitting engagement with the similarly toothed side face of the head 37 of a bracket 38 which is fixed to the inner face of the standard 12 below the cylinder 16. A threaded stem 39 extends from the head 36 through head 37 and carries a wheeled nut 40 which, when tightened, draws the head 36 into engagement with the head 37 and firmly holds the bracket 35 against tilting movement. Therefore, the ring or frame 31 will be held in horizontal position and close to the frame 25 so that as the ring 20 is reciprocated by the piston 17, clean sand shaken through the riddle will drop into the bag.

When the bag is in the position shown in Fig. 1, sand may flow therefrom into the flask and fill the flask. After the flask has been filled, flow of sand from the bag must be stopped. To accomplish this, the lower end portion of the sack or bag is folded upwardly. About its open lower end the bag carries a collar 41 from which extend radiating rods 42. One of these rods has a sleeve 43 at its outer end in which is fixed the lower end of a rod 44. The rod 44 extends vertically with its upper portion slidably engaged through a sleeve 45 carried by the hopper 11 at the front thereof, and a nut 46 upon the rod limits its downward movement through the sleeve. A hook 47 is mounted upon the rod 44 for adjustment longitudinally thereon and, when the operator grasps one or two of the rods or handles 42 of the ring and exerts upward thrust, the ring and the rod will be shifted upwardly and the lower portion of the bag turned upwardly with the ring. After the rod has been shifted upwardly a sufficient distance for the hook to overhang the frame 31 and then allowed to move downwardly, the

hook catches upon the ring and the bag will be held folded and no sand can flow from its lower end. By adjusting the hook along the rod the extent to which the bag is folded may be controlled. When the flask is to be filled, it is merely necessary to shift the rod upwardly, turn it slightly to detach the hook from the ring 31 and then allow the rod to slide downwardly to its full extent. The bag will thus assume the position shown in Fig. 1 and sand may flow from it into the flask. When the riddle becomes clogged with foreign matter screened from sand delivered to it from the hopper 11, the wheel nut 40 is loosened and the ring 31 and the upper portion lowered until the ring 31 hangs vertically from the bracket 38. The frame 25 is then released and lowered, together with the riddle or screen 24 and the riddle removed from the frame and cleaned. The riddle is then replaced upon the frame 25 which is returned to the raised position, where it is secured by the bolt 23, the ring or frame 31 being then swung upwardly to raised position and the nut 40 tightened to hold it in this position.

Having thus described the invention, what is claimed is:

A flask-filling apparatus comprising a base, a standard rising from said base, a hopper supported from said standard and spaced upwardly from the base, a riddle mounted for reciprocating movement under said hopper, a fabric bag under said riddle tapered toward its lower end and having rings at its upper and lower ends, rods projecting from the lower ring, a rod shiftable vertically in front of the hopper and the bag, one rod of the lower ring being connected with the lower end of said rod, and a hook carried by the vertical rod and shiftable thereon to vertically adjusted positions, said hook being shifted vertically with the rod into position for engaging the upper ring and holding a predetermined portion of the lower end portion of said bag in upwardly folded position to close the lower end of the bag and retain sand in the bag.
